(57) **CLAIM**

The ornamental design for a battery case, as shown and described.

DESCRIPTION

FIG. 1 is a perspective view of a design for a battery case.

FIG. 2 is a front view of the design shown in FIG. 1.

FIG. 3 is a rear view of the design shown in FIG. 1.

FIG. 4 is a top view of the design shown in FIG. 1.

FIG. 5 is a bottom view of the design shown in FIG. 1.

FIG. 6 is a first side view of the design shown in FIG. 1; and, FIG. 7 is a second side view of the design shown in FIG. 1. In the drawings, the broken lines are for the purposes of illustrating portions of the battery case that form no part of the claimed design.

1 Claim, 7 Drawing Sheets
